PULL-OFF AND CLAMP FOR THREAD CUTTERS

Richard G. Turner, Worcester, Mass., assignor to
 Crompton & Knowles Loom Works, Worcester,
 Mass., a corporation of Massachusetts

Application March 6, 1946, Serial No. 652,405

1 Claim. (Cl. 139—264)

1

This invention relates to improvements in thread cutting mechanism for looms and it is the general object of the invention to provide an improved form of clamp for the thread.

In weft replenishing looms it is necessary to cut the thread of the outgoing bobbin at a point between the selvage and the bobbin so that part of the thread can be drawn out of the shuttle eye by the descending ejected bobbin. The other part of the thread extends from the cutter to the selvage and should be clamped or in some other way held so that it will not be drawn into the cloth to form an imperfection. In a type of thread cutter which has gone into extensive use provision is made for clamping and cutting the thread, but as heretofore made this type of cutter has not worked entirely satisfactorily with strong relatively inelastic yarns. The reason for this failure is due to pulling of the thread out of the clamp when the cutter is returned to its normal forward position. During this forward movement the cutter moves away from the fell and the resultant tension on the thread dislodges it from the clamp.

It is an important object of my present invention to provide an auxiliary clamp which shall also act as a pulloff to draw an additional amount of yarn from the bobbin prior to cutting. The effect of the auxiliary clamp is to hold an increased length of thread so that even though the thread should slip somewhat when the cutter mechanism is returning to its normal position, some part of the thread will nevertheless remain clamped.

It is another object of the invention to provide improved means by which force may be exerted through the auxiliary clamp against the moving cutter jaw or blade to hold the latter tightly against the stationary blade. This feature of the invention includes a small bushing or sleeve which not only transmits spring pressure to the moving cutter blade, but also serves as a pivot for the auxiliary clamp.

Thread cutters of the type to which this invention more particularly relates have ordinarily been made with leaf springs which hold the primary or main clamp and the cutting jaw in close relationship. It is a further object of the invention to provide an auxiliary clamp so constructed that this leaf spring will not only perform its former functions but also hold the auxiliary

2

clamp during the cutting and clamping operations of the mechanism.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a diagrammatic plan view showing the cloth in a loom, the cutter and clamp provided with my present invention, and a shuttle carrying a depleted bobbin from which the thread to be cut extends to the cloth.

Fig. 2 is a side elevation on an enlarged scale looking in the direction of arrow 2, Fig. 1, showing the cutter and clamping mechanism in normal closed forward position.

Fig. 3 is a perspective view of the thread cutter and its mounting, showing the cutter and clamp in rear open position.

Fig. 4 is an exploded view of the several parts of the thread cutting and clamping mechanism suggesting the manner in which they are assembled and also their relative positions, and

Fig. 5 is a vertical section on line 5—5 of Fig. 2.

Referring particularly to Fig. 1, the cloth 10, warp 11, fell 12 and selvage 13, shuttle 14 and bobbin 15 are shown in the relative positions they occupy during a weft replenishing operation.

The weft thread W to be cut extends from the shuttle eye 16 to the fell and selvage. Located between the shuttle and the cloth is a cutting and clamping mechanism 20 which is ordinarily in the full line position shown in Fig. 1, but when a

replenishing operation occurs mechanism 20 is moved rearwardly to the dotted line position where it can cut and clamp the weft thread W. The thread cutter and clamp is then returned to its normal forward position in which it is farther from the fell than when in its rearward position.

A strand of weft W' extends from the fell to the mechanism 20 and should be held until it can be cut at the selvage by the usual form of selvage cutter not shown. When the yarn W is elastic

it may stretch sufficiently so that the strand W' can be held in the clamp as heretofore made, but when the weft is strong and relatively inelastic, the right end of the strand W' as viewed in Fig. 1 is likely to slip out of the clamp heretofore made.

As shown in Fig. 3 the mechanism 20 is

mounted on a carrier 21 pivoted as at 22 to a lever 23. The latter has provision as at 24 for pivotal mounting on a stationary stud (not shown), and a rearwardly extending arm 25 on lever 23 is adapted for connection with a vertically extending rod (not shown) by which the cutter and clamp is moved. A rod 26 extends upwardly from the cutter and clamp mechanism and is pivoted to a stationary stud (not shown) spaced from the axis of lever 23 so that as the mechanism 20 moves rearwardly there will be a differential movement between it and the lower end of rod 26.

The carrier 21 has a supporting head A to which is held a stationary cutter blade B for cooperation with a pivoted cutter blade C. A clamp or plate D made preferably of some non-metallic material has the rear end thereof positioned by a pin 30 on head A and has the forward end thereof held against vertical motion in a manner to be described. A leaf spring F is secured as at 31 to the carrier 21 and exerts a force toward the head A for the purpose of holding the parts A—D in close relationship. A stud 32 on the forward end of movable cutter C is connected to the lower end of rod 26 so that when the cutting and clamping unit 20 is moved rearwardly the cutting edge 34 of blade C will move downwardly and form a bight with the cutting edge 35 on the bottom of stationary blade B. The thread W enters this bight as the shuttle moves forwardly with the lay not shown, and upon resetting of the mechanism 20 to its normal forward position, the rod 26 causes closing of the cutter jaw C to sever the weft W. The rear part of blade C moves upwardly along the adjacent surface of clamp D to hold the weft thread between the parts C and D.

The matter thus far described, except as noted hereinafter, is constructed and operates in the usual manner.

In carrying my invention into effect I provide an auxiliary clamp E having a forwardly extending arm 40 perforated as at 41 to receive the screw or stud 32. Clamp E has a relatively large hole 42 therein and has a rearwardly projecting finger 43 provided with a preferably upwardly and rearwardly extended rounded surface 44. The part of the clamp E behind the hole 42 is widened as at 45 to receive the thrust of the foot or lower end 46 of the leaf spring F.

A screw or pivot stud H has a head 50 at one end thereof and has the other end thereof threaded at 51 and tapped into the head A. A nut 52 holds the screw H in fixed adjusted position on the head A. The screw passes through a hole 53 in the stationary cutter B located intermediate the front and back ends of the top edge of said cutter B, thereby cooperating with a shoulder or ledge 54 on head A to position the stationary blade. The cutter C also has a pivot hole 55 through which the screw H passes. The holes 53 and 55 are only slightly larger in diameter than the diameter of the screw H and the latter is the pivot around which blade C swings.

Surrounding the screw H is a bushing or sleeve G which extends through a relatively large hole 56 in the primary clamp D and also through the hole 42. The sleeve G constitutes a pivot for the auxiliary clamp E, and engages the inner end of a compression spring 57 the outer end of which engages the screw head 50. The bushing G has its inner end held by spring 57 against the pivoted blade C to force the latter against the stationary blade B. When the parts are assembled as shown in Fig. 5 the spring F exerts a pressure on

all of the parts B—E forcing them toward the head A.

The rearwardly projecting finger 43 of the auxiliary clamp E slides downwardly along the rear part of the outer surface of the primary clamp D when the unit 20 swings rearwardly, thereby forming a thread receiving notch 58 with the primary clamp. When thread W moves forwardly it enters this notch and also the bight formed by the cutter blades, and as unit 20 moves forwardly the blade C and clamp E will be swung in a clockwise direction relatively to head A as viewed in Fig. 2, thereby causing raising of the parts 34 and 43 of the moving cutter C and clamp E, respectively. The finger 43 of the auxiliary clamp is so shaped that during upward movement thereof incident to forward movement of the unit or mechanism 20 it will bend the thread around clamp D, raising the thread and pulling from the shuttle eye. During this operation the auxiliary clamp pulls off an extra length of the thread prior to cutting of the thread by the blades B and C. At the end of the cutting operation therefore as the unit 20 is still in rearward position but moving toward its forward position the strand W' will extend downwardly along the blade finger 34 along the primary clamp D, under the latter, and then upwardly between the clamps D and E to the top rounded edge 44 of the finger 43. Strand W' will then extend to the selvage. Because of the shape and time of operation of the finger 43 a greater length of the strand W' will be held in contact with the primary clamp D than has been possible heretofore, this increase being represented by that part of the thread extending between the clamps D and E. As the unit 20 completes its forward motion it moves away from the fell as already described, and if the weft is relatively inelastic it may slide along the clamp D, but because of the increased amount of the thread held between the clamp the strand W' can slide a considerable distance along the primary clamp and still remain in clamped position between the clamps D and E.

From the foregoing it will be seen that I have provided a simple form of auxiliary clamp which serves to pull off a given length of weft from the bobbin being transferred before the thread is cut by the blades B and C. This additional length of thread permits a larger slippage of the thread along the clamp D without being detached from the mechanism 20 than has heretofore been possible. Clamp E moves transversely of the thread and bends it up along clamp D. It will also be seen that the bushing or sleeve G serves as a pivot for the auxiliary clamp and also transmits the force of spring 57 against the movable cutter blade C. Furthermore, this bushing G also serves to position the forward end of the clamp D and cooperates with the pin 30 to hold clamp D in correct vertical position while at the same time permitting said clamp to slide along said bushing into close relationship with respect to the moving cutter C.

Having thus described my invention it will be seen that changes and modifications may be made therein by those skilled in the art without departing from the spirit and scope of the invention and I do not wish to be limited to the details herein disclosed, but what I claim is:

An auxiliary thread clamp for a loom thread cutting and clamping mechanism having a carrier formed with a supporting head provided with a plate mounted on a pivot stud and a pin spaced therefrom, said carrier having mounted thereon a

spring tending to flex toward the head, said clamp having a pivot hole therethrough fitting the stud and an operating arm extending forwardly from said hole, a rearwardly extending clamping finger having an upwardly facing edge terminating at a distance from the pivot hole less than the distance between said stud and pin, and said clamp having a portion between said finger and hole to engage said spring.
